CLAIM

I claim the ornamental design for a lanyard clasp for identification badges, as shown.

DESCRIPTION

FIG. 1 is a front perspective view of a lanyard clasp for identification badges shown in a position of use, the broken line showing of a figure is for illustrative purposes only and forms no part of the claimed design;

FIG. 2 is a front perspective view;

FIG. 3 is a top view;

FIG. 4 is a front plan view;

FIG. 5 is a right side view;

FIG. 6 is a bottom view;

FIG. 7 is a rear plan view;

FIG. 8 is a left side view;

FIG. 9 is a front perspective view of a lanyard clasp for identification badges showing a second embodiment of my new design;

FIG. 10 is a top view of FIG. 9;
FIG. 11 is a front plan view of FIG. 9;
FIG. 12 is a right side view of FIG. 9;
FIG. 13 is a bottom view of FIG. 9;
FIG. 14 is a rear plan view of FIG. 9;
FIG. 15 is a left side view of FIG. 9;
FIG. 16 is a front perspective view of a lanyard clasp for identification badges showing a third embodiment of my new design;
FIG. 17 is a top view of FIG. 16;
FIG. 18 is a front plan view of FIG. 16;
FIG. 19 is a right side view of FIG. 16;
FIG. 20 is a bottom view of FIG. 16;
FIG. 21 is a rear plan view of FIG. 16;
FIG. 22 is a left side view of FIG. 16;
FIG. 23 is a front perspective view of a lanyard clasp for identification badges showing a fourth embodiment of my new design;
FIG. 24 is a top view of FIG. 23;
FIG. 25 is a front plan view of FIG. 23;
FIG. 26 is a right side view of FIG. 23;
FIG. 27 is a bottom view of FIG. 23;

FIG. 28 is a rear plan view of FIG. 23;
FIG. 29 is a left side view of FIG. 23;
FIG. 30 is a front perspective view of a lanyard clasp for identification badges showing a fifth embodiment of my new design;
FIG. 31 is a top view of FIG. 30;
FIG. 32 is a front plan view of FIG. 30;
FIG. 33 is a right side view of FIG. 30;
FIG. 34 is a bottom view of FIG. 30;
FIG. 35 is a rear plan of FIG. 30;
FIG. 36 is a left side view of FIG. 30;
FIG. 37 is a front perspective view of a lanyard clasp for identification badges showing a sixth embodiment of my new design;
FIG. 38 is a top view of FIG. 37;
FIG. 39 is a front plan view of FIG. 37;
FIG. 40 is a right side view of FIG. 37;
FIG. 41 is a bottom view of FIG. 37;
FIG. 42 is a rear plan view of FIG. 37; and,
FIG. 43 is a left side view of FIG. 37.
